UNITED STATES PATENT OFFICE.

BENJAMIN H. MARCUS, OF BROOKLYN, NEW YORK.

COMBINED BUCKLE AND PURSE.

Application filed February 1, 1926. Serial No. 85,134.

This invention relates to improvements in belt buckles and has for its main object the provision of a belt buckle in combination with a purse.

5 Another object of this invention is to provide a belt buckle having a purse hinged thereto, said purse being adapted to be tightly closed and substantially waterproof when the belt is worn to support a bathing suit.

10 Other objects and novel features of the invention will become more apparent and fully described as the specification proceeds.

In the drawings forming a part of this specification,

15 Figure 1 is a perspective view of such a belt buckle attached to a belt at one end, the other end of the belt being shown in locked engagement with the buckle,

20 Figure 2 is a perspective view of the belt buckle with the hinged purse shown in open position,

Figure 3 is a cross section taken on line 3—3 Figure 1,

25 Figure 4 is a detail view of the base portion of the combined buckle and purse; and

Figure 5 is a detail view of the member connecting the combined belt buckle and purse to the belt locking member.

30 Referring to the drawings in detail, 10 indicates a combined belt buckle and purse, comprising a cover or lid 11 hinged as at 12 by means of a pin 13 passing through the end walls 14 of the cover 11 and through

35 ears 15 projecting upwardly from a base portion 16. A change compartment or purse 17 is formed in the cover 11 between an extension 18 of the said cover bent around internally and the inner surface of the top wall or roof 19 of the lid 11. Coins may be inserted into the purse through an opening 20 in the extension 18 when the lid is in open position as shown in Figure 2 of the drawings. A belt 22 is attached to one end

40 of the base 16 as at 23 and may be held and locked in place around the wearer by the usual locking portion 24, hingedly attached to a connecting member 25, removably and pivotally attached to the base 16 by means

45 of a raised portion or pin 25^a in the member 25 and an opening 16^a in the base, and projections 26 on said member 25 passing through arcuate slots 27 in the base 16. These slots 27 have enlarged openings 28

55 through which the prongs or projections 26 may be easily inserted or withdrawn when

assembling or disassembling the base and belt locking mechanism. In assembling these parts all that is necessary to do is to insert the prongs 26 into the openings 28 and the pin 25^a into the hole 16^a and revolve the member 25 until the said prongs abut the ends of the slots 27 and the said member 25 will be frictionally held in place by lips 29 that are slightly bent downwardly and partly surround the slots 27. A raised portion or bead 30 on the base 16 surrounds the periphery of the lid to prevent any coins from slipping out of the purse and to make same substantially watertight and a lip or projection 31 struck up from the base 16 overlies a portion of the front edge of the lid and tends to maintain same in locked position. The purse may be opened by inserting the thumbnail under the cover as at 32, Fig. 1.

From the foregoing it will be seen that I have provided a combined belt buckle and purse of simple construction and easy to manipulate in which money may be kept and maintained in waterproof condition when the belt is worn to support a bathing suit.

Having described my invention, which I claim and desire to secure by Letters Patent is:

1. In a purse, a base, a cover hingedly associated with the base, a projection integral with the cover and bent inwardly therefrom to form a compartment within the said cover, a bead on the base surrounding the cover when said cover is closed and a projection on the base associated with the cover to keep same in closed relation with the base.

2. In a purse adapted to be attached to a belt, a base, a cover hingedly associated with the base, and a belt and purse connecting member mounted on the base and adapted to be detached therefrom by a pivotal movement of the said connecting member on the base.

3. In a purse adapted to be attached to a belt, a base, a cover hingedly associated with the base, a belt and purse connecting member mounted on the base and adapted to be detached therefrom by a pivotal movement of the said connecting member on the base, and means on the base and the connecting member to frictionally retain the said base and connecting member in locked relation.

4. In a purse adapted to be attached to a belt, a purse and belt connecting member mounted on the purse and adapted to be de-

tached therefrom by a pivotal movement thereof on the base and means on the purse and connecting member to retain the connecting member in locked relation with the 5 purse.

5. In a purse adapted to be attached to a belt, a base, having arcuate slots therein, lips on the base partly surrounding the said slots and slightly bent downwardly and adapted 10 to be detachably connected by pivotal movement to a belt and purse connecting member

pivotaly mounted on said base and projections on the connecting member adapted to be inserted into the said slots over the lips to frictionally retain the connecting member in locked relation with the purse when the connecting member is revolved around its pivot.

In testimony whereof I hereunto affix my signature.

BENJAMIN H. MARCUS.
